UNITED STATES PATENT OFFICE.

HENRY FURSTE, OF CINCINNATI, OHIO, ASSIGNOR TO THE UNITED STATES PRINTING AND LITHOGRAPH COMPANY, OF CINCINNATI, OHIO, A CORPORATION OF OHIO.

CARTON.

Application filed August 6, 1920. Serial No. 401,677.

To all whom it may concern:

Be it known that I, HENRY FURSTE, a citizen of the United States of America, and resident of Cincinnati, in the county of 5 Hamilton and State of Ohio, have invented a new and useful Improvement in a Carton, of which the following is a specification.

An object of my invention is to provide a carton formed from a blank having a series 10 of flaps, which may be readily and positively locked in the assembled form.

Another object is to provide a carton of the type described in which the blank is formed in such wise that a minimum of 15 stock is employed.

Another object is to provide a carton that can be employed for display purposes and which when so employed will have its parts positively locked in position for such use.

20 These and other objects are attained by the means described herein and disclosed in the accompanying drawing in which:

Fig. 1 is a plan view of an unassembled carton embodying my invention.

25 Fig. 2, is an enlarged perspective view of an assembled carton shown in Fig. 1.

The carton A has a top a, a back b, an outer bottom ply c, an outer front ply d, an inner front ply e and an inner bottom ply f attached to and adjoining one another and being set off from one another by the scored 30 lines b', c', d', e' and f' respectively. The top flap a² is attached to the top a and is set off therefrom by the scored line a'.

35 The inner bottom ply f has a sectional ply f² thereof extending and engaging the back b, the fractional ply f³ extending but a short distance from the inner front ply and outer front ply when assembled. The end plies g are attached to the ends of the back b and are set off from the back by the scored lines 40 g'. A bottom flap h is formed on one end ply and a bottom flap h' on the other end ply. Both flaps are set off from the end plies by the scored lines h² and are adapted to lie between the inner bottom ply and the outer bottom ply when the carton is assembled. The flap h' is on the same side of the carton as the fractional ply f³ of the inner bottom 45 ply f and has a finger h³ formed thereon adapted to assume a position over the fractional ply f³, and the lug h⁴ adjacent to the

finger and between such finger and the end 55 ply g being adapted to be retained between the fractional ply f³ and the outer bottom ply c, when the carton is assembled. The main object is to have the finger and lug engage the opposite sides of the inner bottom ply. The laps k extend from the end plies g and are set off therefrom by the 60 scored lines k', and are adapted to lie between the inner front ply e and outer front ply d when the carton is assembled. The flanges m are attached to the end plies and are set off therefrom by the scored lines 65 m' and have extending from them the tongues n, set off by scored lines n', and the support plies p, adjacent to the tongues n and set off by the scored lines p'.

The carton is set up as follows:

The end plies g are bent toward one another and at right angles to the back b upon scored lines g', the flaps h and h' lying upon the outer bottom ply c. The laps k are bent toward one another upon the scored 70 lines k'. The outer front ply d is then bent upward on scored line d' and at right angles to the outer bottom ply and engages the outer surface of the laps k. The inner front ply e is then bent downward and inwardly 75 upon the scored line e' and engages the inner surfaces of the laps k, thereby enclosing the laps k between the inner front ply and outer-front ply and enclosing flaps h and h' between the outer bottom ply and the inner bottom ply. To accommodate this 80 movement of inner front ply e, the inner bottom ply f is bent upon the scored line f' and away from the outer bottom ply. The inner bottom ply is then pushed down upon 85 the outer bottom ply. The finger h³ is then drawn upward until it is disposed above the fractional ply f³ and the outer bottom ply at which time the finger is released, thereby securing a fractional ply f³ between 90 the lug h⁴ and finger h³ on the flap h'. The sectional ply f² abuts the outer front ply d and the back b, the frictional contact between these parts preventing unfolding of 95 the carton. Altho the flaps h and h' and sections f² and f³ are shown of dissimilar construction, both flaps may be given the same construction either as shown at h or h', and the inner bottom ply f be made thruout 100

in proper form according to which flap construction is used.

The top flap a^2 is employed to secure the top upon the flanges m and upon the carton by its frictional engagement with the inner front ply.

When the carton is to be used for display purposes the flanges m are bent outward from the carton and the support plies p are turned 10 upon the scored line p' until the support plies are in engagement with and secured between the end plies g and the flanges m . The tongues n are inserted between the flaps h or h' and the outer bottom ply and 15 secures the carton in display form, the ends of flanges m and support plies n adjoining scored line n' engaging the floor of the display rack or window.

What I claim is:

20 1. A folded carton comprising a back, end plies attached to the back, laps on the end plies, bottom flaps attached to the end plies, a finger and a lug on one of the flaps, an outer bottom ply, an inner bottom ply, an 25 outer front ply, an inner front ply, the laps being adapted to be inserted between the inner front ply and the outer front ply, the bottom flaps being adapted to extend between the inner bottom ply and the outer 30 bottom ply, the finger and the lug on the one bottom flap engaging opposite sides of the inner bottom ply, the inner bottom ply covering the other flap and abutting the back, flanges on the end plies, tongues on the 35 flanges, and support plies on the flanges, the support plies being adapted to be turned upon the flanges and be secured between and in contact with the flanges and the end plies by inserting the tongues between the outer bottom ply and the flaps.

40 2. A folded carton comprising a back, an end ply attached to the back, a flange on the end ply, a tongue on the flange, a support ply on the flange, an outer bottom ply, 45 and an inner bottom ply, the support ply being adapted to be turned upon the flange and be secured between and in contact with the flange and the end ply by inserting the tongue between the outer bottom ply and the inner bottom ply.

50 3. A folded carton comprising a back, end plies attached to the back, laps on the end plies, flanges on the end plies, tongues on the flanges, support plies on the flanges, an outer bottom ply and an inner bottom ply, an inner front ply, an outer front ply, the laps being adapted to be inserted between the inner front ply and the outer front ply, the support plies being adapted to be turned 55 upon the flanges and to extend between and contact with the flanges and the end plies, and the tongues being adapted to be inserted between the outer bottom ply and the inner bottom ply.

60 4. A folded carton comprising a back, an

end ply attached to the back, a lap on the end ply, a bottom flap on the end ply, a finger on the flap, a lug on the flap, an inner bottom ply, an outer bottom ply, an inner front ply and an outer front ply, the 70 lap on the end ply being adapted to be inserted between the inner front ply and the outer front ply, and the finger and the lug on the flap being adapted to engage opposite sides of the inner bottom ply.

75 5. A carton comprising a back, end plies attached to the back, laps on the end plies, flanges on the end plies, tongues on the flanges, support plies on the flanges, bottom flaps on the end plies, a bottom, and a front, the laps being adapted to be retained adjacent the front, the bottom flaps being adapted to lie over the bottom, the tongues being adapted to be inserted between the bottom and the bottom flaps, and the support plies 80 being adapted to be turned on the flanges and to extend between the flanges and the end plies.

85 6. A carton comprising a back, an end ply attached to the back, a lap on the end ply, a flange on the end ply, a tongue on the flange, a support ply on the flange, an outer bottom ply, an inner bottom ply, an outer front ply, an inner front ply, the lap on the end ply being adapted to be inserted between the inner front ply and the outer front ply, the inner bottom ply being adapted 90 to abut the back, the tongue being adapted to be inserted between the outer bottom ply and the inner bottom ply, and the support ply being adapted to be turned upon the flange and to extend between the flange and the end ply.

95 7. A carton comprising a back, an end 105 ply attached to the back, a lap on the end ply, a flange on the end ply, a tongue on the flange, a support ply on the flange, a bottom flap on the end ply, a finger on the flap, a lug on the flap, an inner bottom ply, an outer bottom ply, an inner front ply, 110 and an outer front ply, the lap on the end ply being adapted to be inserted between the inner front ply and the outer front ply, the finger and the lug on the flap being adapted to engage opposite sides of the inner bottom ply, the tongue being adapted to be inserted between the outer bottom ply and the inner bottom ply, and the support 115 ply being adapted to be turned upon the flange and to extend between the flange and the end ply.

120 8. The combination with a carton having an end ply and a bottom, of a flange on the end ply, a tongue on the flange and a support ply on the flange, the tongue and the support 125 ply being adapted to be turned upon the flange, the tongue being adapted to assume a position adjacent to the bottom and to thereby retain the flange in position beside and in substantial parallelism with 130

the end ply, and the support ply being adapted to extend between the end ply and the flange.

9. The combination with a carton having 5 an end ply, of a flange on the end ply adapted to be turned on the end ply, a support ply on the flange adapted to be turned on the flange and to extend between the flange

and the end ply, and means to retain the flange in turned relation to the end ply, and 10 to retain the support ply in turned relation to the flange.

In witness whereof, I have hereunto subscribed my name this 4th day of August, 1920.

HENRY FURSTE.
